UNITED STATES PATENT OFFICE.

WILLIAM WALLACE DICKINSON, JR., OF LITTLE ROCK, ARKANSAS.

BRICK-KILN CONSTRUCTION.

Application filed May 28, 1926. Serial No. 112,227.

This invention relates to brick-kiln construction in general; but has more specific reference to improvements in the forms, arrangements, and methods of construction, hitherto employed for such kilns, typical examples of late types of which are illustrated and described in two United States Letters Patent, issued to me, and respectively identified as No. 1,305,447, dated June 3, 1919, and No. 1,355,821, dated October 19, 1920.

The practice heretofore followed in brick-kiln construction, has required such arrangements, and so great quantities, of permanent structures, at, below, or above, the base of the kilns, as to involve excessive expenditures for kiln construction; to interfere with the flexibility of the plant, particularly as regards changes in the sizes or arrangements of the individual kiln units; and to lessen the handling capacity and efficiency of mechanical brick-handling equipment, such as mechanical setters. Also, the output per unit of kiln capacity heretofore has been too small, and the percentage of loss, due to "spalls" and overburned and underburned bricks, has been too great; rehandling and restorage of the bricks between the kilns and the transporting or shipping means, has been necessary, owing to the lack of provision for leaving the bricks in the kilns in which they were burned, until such time as they were to be transported to points of delivery; and such rehandling and restorage have affected correspondingly the amount of ground space required for a brick plant.

Numerous improvements in kiln construction have been attempted from time to time, particularly in the way of efforts to increase the efficiency of the kilns as regards minimizing heat losses and promoting effective fuel utilization; but many of these so-called "improvements" have been incapable of effecting any real saving, if interest on plant investment, operating costs, waste, and rate and grade of output, be taken into account. In utilizing the hot waste gases from one kiln unit, for doing useful work in an adjacent unit or units, the practice hitherto has been either to admit such gases at the top of the secondary kiln and discharge them at its bottom, or to admit them at the bottom and discharge them at the top. With

either arrangement, sufficient draft must be provided to overcome the natural tendency of the hot gases to rise, and to draw them downward; permanent structures are required for each kiln unit and between the units; and in various ways the results secured in practice are far from satisfactory.

The principal objects of the present invention are to provide a form of brick-kiln construction, and a method of producing it, in which

(a) No transverse passages, in, through, over, or under, the individual kiln units, are required, other than the archways in which combustion takes place;

(b) One temporary division wall separates each two adjacent kiln units, and extends from the floor to a height below that of the under side of the top covering, thereby affording a passage for the hot gases from a kiln that is being fired to the upper portion of an adjacent kiln, heating the upper bricks in the latter, and causing an up-draft therein;

(c) Since there are no permanent division walls, each kiln unit may be made of any desired length, and is intended to be completely demolished, preferably by mechanical means, when the bricks are being removed;

(d) No artificial floor, and no underground piping, tunnels, or other underground apparatus or construction, are necessary;

(e) Underburning or overburning of the bricks in the "corners" adjacent the division walls, is avoided;

(f) The capacity and efficiency of mechanical brick-handling apparatus, when used in either constructing or demolishing kilns that are arranged and constructed in accordance with my invention, are increased, and the operating cost thereof is decreased; and

(g) The up-draft created in each kiln unit, by the passage, through the upper part thereof, of the hot, burned gases from another unit, promotes "water smoking" of all of the bricks in the secondary kiln, and minimizes formation of "cold centers" in the kiln units.

The means by which the foregoing and other objects are accomplished by my in-

vention, and the method employed for their accomplishment, readily will be understood from the following description on reference to the accompanying drawings, in which—

5 Fig. 1 is a plan view, showing a preferred arrangement for two adjacent, similar rows of kiln units, the locations of the units of the upper row being indicated by dotted lines, and the first unit in the lower row
 10 starting at the left, being shown empty; the second unit as having had the burned bricks removed therefrom, down to the side walls of the combustion arches; the third unit as having had the top removed, to expose the
 15 burned bricks underneath; and the fourth, fifth and sixth units as being in the condition that would exist if said units were completed, and the fourth unit were in process of burning.

20 Fig. 2 is a side elevation of the same, showing the shed that is usually provided over the kilns, and indicating the presence of a mechanical brick-handling device.

25 Fig. 3 is a sectional side elevation, on a larger scale, of the third and fourth kiln units, and a portion of each of the second and fifth units, shown in Figs. 1 and 2, the section being taken substantially on line III—III of Fig. 1.

30 Fig. 4 is a sectional elevation, also on an enlarged scale, taken substantially on line IV—IV of Fig. 1.

Referring now to the drawings in detail, it will be seen that in Fig. 1 six kiln units, 35 respectively indicated by reference numerals 5, 6, 7, 8, 9 and 10, are shown as constituting each row,—the reason for this being that, while burning of the kilns customarily is continued for seven days a week, only six 40 days are devoted to brick handling, kiln construction and demolition, and other like work, and each row of kilns may therefore well be designed on a six-day basis. Manifestly, only a single row of kilns may be 45 provided for if desired, and for that reason the duplicate row is shown in dotted lines in the drawings, and no specific reference will be made thereto hereinafter. Over the 50 area intended to be occupied by the kilns, a shed 11 preferably is erected, and, upon runways supported by the posts 12 which carry the roof of the shed, is movably mounted a traveling bridge 13, having thereon a traveling mechanical setter 14, of any 55 preferred type, adapted to serve all parts of the kiln units of each row, and preferably being capable of use both for placing the bricks in the kilns, and for removing them therefrom.

60 At the end of the row at which construction of the kilns is intended to be started (Figs. 1 and 2 indicate this as being the left-hand end), a wall 15, which preferably is permanent, is constructed of burned 65 bricks, said wall being of the over-all height

and width that is predetermined for the kilns, and preferably being chinked and daubed with moist clay, or otherwise treated, to prevent inflow of air or outflow of the gases, and to minimize the transmission of 70 heat therethrough. The green bricks are put in place in the first kiln unit by means of the mechanical setter, leaving the usual archways 16, and said unit may be made of any desired length, and of any width 75 permitted by the width of the shed 11. After having set all of the bricks intended to be placed in the first kiln unit, the side or scove-casing walls 17 and 18, of substantially the same length and height as the 80 kiln unit, and formed of burned bricks, are laid by hand, and are suitably chinked and daubed, or otherwise treated, in a manner similar to that employed with the bricks forming the permanent end wall 15; and a 85 temporary division wall 19, of unburned bricks, is hand-laid similarly, but without being chinked, daubed, or otherwise treated, said wall being extended between, but can be bonded into, side walls 17 and 18, but 90 the height of wall 19 being less than that of the green bricks in the kiln, by a distance preferably equal to the overall thickness of the bricks handled each time by the mechanical setter, which thickness ordinarily is about 36 inches. Thus, an outlet opening 20 is provided, through which some of the hot gases may pass from the kiln unit, either into an adjacent unit, or, in the case of the last kiln in a row, into the atmosphere. 95 Also, since, as just stated, the division wall 19 is made of unburned bricks, and the cracks between the bricks are not filled, some of the hot gases pass through these cracks into the adjacent kiln unit, and such "short circuiting," of the hot gases becomes more pronounced as the bricks in the division wall become heated, and are thus caused to shrink. The kiln unit is completed by covering its top with a platting of 100 burned bricks 21, preferably about three courses deep, and said top covering can be chinked and daubed, or otherwise treated, in a manner similar to that employed with walls 15, 17 and 18. This is not absolutely 105 necessary but saves fuel.

Each kiln unit is constructed in the manner just described for the first unit, with the exception that only the first unit in a 110 row comprises any permanent structure, such as the end wall 15, and, as has been stated, said wall need not necessarily be permanent. After the burning of a kiln unit has been completed, which usually requires about five days, enough of its top preferably is removed to permit the outlet 20 leading therefrom to be bricked up, but this is not absolutely necessary and when such unit has cooled sufficiently, its top may be entirely removed, either with the mechanical 115

setter or by hand, and the burned bricks may be left stored in the kiln unit until they are required, when they may be removed with the mechanical setter, or by hand, directly from such storage to trucks or other transporting means. As the burned bricks are taken out of the kiln unit, its side walls and rear division wall are demolished at the same time, and the bricks comprising said walls are either laid aside for subsequent use in kiln construction, or may be cleaned, and put in with the fresh-burned bricks. Preferably, construction of the kiln units is so planned, relative to the times at which it is intended to fire the respective ones, that ordinarily there are at least six completed units ahead of the one being fired, so that some of the gases from the unit in which combustion is taking place, pass from said unit into the upper part of a second unit, and thence into the upper part of a third, and so on, before all of the hot gases are wasted into the air. Since the tops of the kiln units are not absolutely gas-tight, especially after being heated, a certain percentage of the hot gases, in fact the greater portion of them, passes into the air through the kiln tops, but enough goes over from each kiln unit, through the opening 20, into the adjacent unit, to cause the bricks in the upper part of the latter to become heated, thereby creating an up-draft. This eliminates any likelihood of a "cold center", and effects a saving in fuel. Any number of kiln units can be fired at any one time and the units can each be in different stages of burning, in fact this method is preferable.

Manifestly, the improvements referred to herein are independent of the sort of fuel that may be used in firing the kilns, and of any apparatus that may be employed in connection with the combustion process, and it has not been thought necessary or desirable to illustrate or describe in the present application any firing means or method. It should be noted, however, that, so far as my improved type and process of kiln construction are concerned, no artificial floor, or other surface or sub-surface structure or apparatus, is required, and the kilns may be constructed directly upon any level area of hard ground that is suitably drained.

Various modifications of minor details of the improvements referred to herein, doubtless readily will suggest themselves to those skilled in this art, and I therefore do not desire to have the scope of my invention limited to any details that are not specifically claimed.

Having now fully disclosed the invention, what I claim is:

1. A plurality of adjacent units made up of brick placed for burning, having a division wall initially of unburned brick, between each two thereof, said wall being of

less height than the said units, thereby providing initially a passage-way above said wall for gases of combustion between said units, and as burning and shrinkage of said wall progresses, providing additional direct 70 passageways through said wall.

2. A plurality of adjacent units made up of brick placed for burning, side walls therefor, and a roof therefor, said units having a division of less height than said units, thereby providing initially a passageway above 75 said wall for gases of combustion between said units, and as burning and shrinkage of said wall progresses, additional direct passageways through said walls.

3. A plurality of adjacent units of brick placed for burning, firing channels through said units, side walls, and a roof, said units having a division wall initially of unburned brick, between each two thereof, said wall being of less height than said units, thereby providing initially a passageway above 80 said wall for gases of combustion between said units, and as burning and shrinkage of said wall progresses, additional direct passageways through said walls.

4. The method of brick-kiln construction, comprising laying up a unit section of unburned bricks in open fashion for burning, providing through the lower portion thereof, during such laying, suitable channels for firing, building along each side of said section a closely laid and daubed wall of burned brick, of the full height of said unit, closing at least one end of said section with a 95 closely laid wall of unburned brick of less height than the height of the said unit, and covering the entire unit with closely laid and chinked layers of burned brick, whereby after burning said unit may be removed in 100 its entirety.

5. The method of burning brick, comprising providing an end wall, laying up thereagainst a unit section of unburned brick, in open fashion for burning, providing through the lower portion thereof during such laying suitable firing channels, building along each side of said section a closely laid and daubed wall of burned brick of the full 110 height of said units, closing the end of said unit section with a division wall of closely laid unburned brick, of less height than said unit, covering said unit with closely laid and chinked layers of burned brick, burning the brick in said unit, and thereafter removing the entire structure.

6. The method of burning brick, comprising providing an end wall laying up thereagainst a unit section of unburned brick, in open fashion for burning, providing through the lower portion thereof during such laying suitable firing channels, building along each side of said section a closely laid and daubed wall of burned brick of the full 125 height of said units, closing the end of such 130

unit section with a division wall of closely laid unburned brick, of less height than said unit, covering said unit with closely laid and chinked layers of burned brick, building progressively additional similar units, each using the division wall of the preceding unit as an initial wall, burning the bricks

in each of said units in similar progression, and thereafter removing in its entirety, each of said units, in similar progression.

10

In testimony of the foregoing, I affix by signature hereunto.

WILLIAM WALLACE DICKINSON, JR.
